UNITED STATES PATENT OFFICE.

EVEN J. ROHNE, OF MINNEAPOLIS, MINNESOTA.

SAD-IRON SUPPORT.

1,213,263.

Specification of Letters Patent. Patented Jan. 23, 1917.

Application filed March 27, 1916. Serial No. 86,875.

To all whom it may concern:

Be it known that I, EVEN J. ROHNE, a citizen of the United States, residing at Minneapolis, in the county of Hennepin and State of Minnesota, have invented certain new and useful Improvements in Sad-Iron Supports; and I do hereby declare the following to be a full, clear, and exact description of the invention, such as will enable others skilled in the art to which it appertains to make and use the same.

My invention relates to improvements in supports for sad-irons; and, to this end, the invention consists of the novel devices and combinations of devices hereinafter described and defined in the claims.

In the accompanying drawings, which illustrate the invention, like characters indicate like parts throughout the several views.

Referring to the drawings, Figure 1 is a side elevation of a sad-iron having the invention applied thereto, some parts being shown in different positions by means of broken lines; Fig. 2 is a view, partly in plan and partly in horizontal section taken on the line x^5-x^5 of Fig. 5; Fig. 3 is a view in side elevation showing the opposite side of the sad-iron from that shown in Fig. 1; Fig. 4 is a rear end elevation of the parts shown in Fig. 1; Fig. 5 is a front end elevation of the support removed from the sad-iron, some parts being illustrated by means of broken lines and some parts removed; Fig. 6 is a front end elevation of the parts shown in Fig. 1; and Fig. 7 is a perspective view of the support removed from the sad-iron, some parts being illustrated by means of broken lines.

Of the parts of the electric sad-iron illustrated, it is important to note the body 1, handle 2, bracket 3 to which the handle 2 is secured, screws 4 which detachably connect the handle bracket 3 to the body 1, and socket 5 for receiving the customary plug, not shown, to which the electric iron is attached. While an electric sad-iron is illustrated in the drawings, it is, of course, understood that the invention may be applied to any form or make of sad-irons.

Referring now to the invention, the numeral 6 indicates a flat body member inter-

posed between the handle bracket 3 and the body 1 and is rigidly but detachably secured in position by the screws 4, which are passed through apertures 7 formed in said body member. The front end of the body member 6 is bent upward to form a bracket 8 and the rear end thereof is bifurcated to afford a pair of spring prongs 9. The free ends of these prongs 9 are rolled to afford a pair of axially alined bearings 10, which extend transversely of the sad-iron. On the inner longitudinal edge of one of the prongs 9 is integrally formed a bearing 11, which extends at right angles to the bearings 10 and is axially alined with a vertically elongated bearing 12 formed in the bracket 8.

Journaled in the bearings 10, is a rod 13, the ends of which are bent laterally to form a pair of legs 14, which swing to and from lowered positions longitudinally of the sad-iron, inward of the longitudinal edges thereof. The free end of each leg 14 is bent to afford a foot 15, which, when the legs 14 are lowered, extends under the sad-iron, as best shown in Figs. 4 and 5. Stops 16 are formed by bending the legs 14 at their junction with the rod 13. These stops 16 engage the top of the body 1, when the legs 14 are raised, and hold the same in rearwardly and upwardly extended positions, as best shown in Figs. 1 and 3.

A shaft 17 is journaled in the bearings 11 and 12 and the rear end thereof is bent to form a cam finger 18, which engages one of the legs 14, as best shown in Figs. 4 and 7. The forward end of the shaft 17 is bent laterally to form a leg 19, which is identical with the legs 14, but swings at a right angle thereto. The lower end of the leg 19 is bent to form a foot 20, which, when the leg 19 is lowered, extends transversely under the point of the iron, as best shown in Figs. 1, 4 and 5.

A pinion 21 is secured to the shaft 17 between the bracket 8 and leg 19. Intermediately fulcrumed to the bracket 8, for movement transversely of the handle 2, is a lever 22 having, at its upper end, a finger piece 23 and having, at its lower end, a toothed segment 24, which meshes with the pinion 21. A stop lug 25, projecting from

the bracket 8, extends into a segmental slot 26 formed in the lower end of the lever 22 and limits the swinging movement thereof in either direction. The legs 14 and 19 are 5 normally and yieldingly held raised by a coiled spring 27 anchored, at one, end, to the upper end of the bracket 8, and, at its other end, to the upper end of the lever 22. The cam finger 18, acting upon the respective leg 14, raises the legs 14 simultaneously 10 with the raising of the leg 19.

The leg 19 is lowered into an operative position by pressing downward on the finger piece 23 and as the leg 19 is thus positively lowered, the legs 14 will follow into like positions under the action of their own weight. It is important to note that this finger piece is located close to the front end 15 of the handle 2, so that the same may be engaged by the thumb of the operator's hand grasping the handle 2. By thus locating the finger piece 23, the legs 14 and 19 are lowered by a very natural and easy movement of the hand. When the legs 14 20 and 19 are lowered, their feet extend under the sad-iron and are frictionally held between the body of the iron and the support upon which they rest. Under the weight 25 of the sad-iron, the prongs 9 yield and the front end of the shaft 17 raises in the bearing 12, sufficiently to allow the sad-iron to rest directly and securely upon the legs 15 and 20. When the sad-iron is lifted, the 30 spring 20, acting upon the lever 22, moves the segment 24 over the pinion 21 which, in turn, rotates the shaft 17 and raises the legs 14 and 19. When the legs of the support are raised, they are entirely out of the way and do not, in any way, hinder the 35 operator or obstruct his view of the sad-iron in guiding the same over the work.

The above described device, while extremely simple and of extremely small cost to manufacture, can be very easily applied 40 to and removed from a sad-iron.

What I claim is:—

1. A sad-iron support including a plurality of movable legs secured to a sad-iron, said legs having feet on which the sad-iron 45 rests when the legs are lowered.

2. A sad-iron support including a plurality of movable legs secured to a sad-iron, yielding means tending to raise the legs, said legs having feet on which the sad-iron 50 rests when the legs are lowered, the weight of the sad-iron on said feet holding the legs lowered against the tension of said yielding means.

3. A sad-iron support including a plurality of movable legs secured to a sad-iron for swinging movement and limited end-wise movement, said legs having feet on which the sad-iron rests when the legs are lowered.

4. A sad-iron support including a plural- 65 ity of movable legs secured to a sad-iron, said legs having feet on which the sad-iron rests when the legs are lowered, and yielding means tending to raise the legs.

5. A sad-iron support including a plural- 70 ity of movable legs secured to a sad-iron, said legs having feet on which the sad-iron rests when the legs are lowered, yielding means tending to raise the legs, and means for positively lowering one of said legs. 75

6. The combination with a sad-iron having a removable handle-equipped bracket, and means detachably securing said bracket to the sad-iron, of a support for the sad-iron including a body member having legs, 80 said body member being interposed between said bracket and the body of the sad-iron and detachably secured thereto by the means securing said bracket to the sad-iron.

7. A sad-iron support including three 85 legs, two of said legs being mounted at the heel of a sad-iron for movement longitudinally of the sad-iron and the other of said legs being mounted on the sad-iron for movement transversely of and at the point 90 of the sad-iron.

8. A sad-iron support including three legs, two of said legs being mounted at the head of a sad-iron for movement longitudinally of the sad-iron and the other of 95 said legs being mounted on the sad-iron for movement transversely of and at the point of the sad-iron, said legs having feet which, when the legs are lowered, extend under the sad-iron. 100

9. A sad-iron support including a movable leg secured to a sad-iron, and means for actuating said leg, including a pinion on said leg and a finger piece having a toothed segment meshing with said pinion. 105

10. A sad-iron support including a body member mounted on a sad-iron and having a pair of yielding prongs, a pair of movable legs connected for common movement and mounted on said prongs, a shaft journaled on said body member and having at one end a cam engageable with one of said legs for raising said connected legs, and having at its other end a leg, the end of the shaft to which the respective leg is attached 110 having a slight vertical movement, a spring tending to rotate the shaft in a direction to raise the legs, and means for rotating the shaft against the tension of said spring to lower the legs, said legs having feet on 115 which the sad-iron rests when the legs are lowered.

11. A sad-iron support including a pair of legs mounted at the heel of a sad-iron and a leg mounted at the point thereof, said legs 120 being movably mounted and, when raised, extending inwardly of the longitudinal edges of the sad-iron. 125

12. A sad-iron support including a pair of legs mounted at the heel of a sad-iron and a leg mounted at the point thereof, said legs being movably mounted, the legs at the heel of the sad-iron, when raised, extending one on each side of the handle of the sad-iron and inwardly of the longitudinal edges of the sad-iron and the leg at the

point of the iron, when raised, extending in front of said handle.

In testimony whereof I affix my signature in presence of two witnesses.
